UNITED STATES PATENT OFFICE.

HENRY O. REESE, OF BALTIMORE, MARYLAND.

SHEET-METAL ROOFING.

SPECIFICATION forming part of Letters Patent No. 638,064, dated November 28, 1899.

Application filed September 16, 1899. Serial No. 730,684. (No model.)

To all whom it may concern:

Be it known that I, HENRY O. REESE, a citizen of the United States, residing at Baltimore, in the State of Maryland, have invented 5 certain new and useful Improvements in Sheet-Metal Roofing, of which the following is a specification.

This invention relates to an improved standing joint for tin roofs.

10 The object of the invention is to provide an improved form of standing expansible joint for metal roofs, first, that will admit of being readily soldered; second, that will always be easy of inspection to detect defects and read- 15 ily repaired when defects are found to exist; third, whose formation will be such as not to break or crack the metal at the cross-seams; fourth, which, while comparatively low in its upward projection, will have no turned-down 20 folds below which dirt and moisture may accumulate to cause rust, and, finally, fifth, which requires no more metal for its formation than has heretofore been used in ordinary standing joints.

25 Referring to the accompanying drawings, Figure 1 shows several adjoining strips of tin roofing with upturned edges for forming standing joints and also showing one of my improved joints formed. Fig. 2 is a cross- 30 section of a portion of two adjoining strips of tin-plate with upturned edges in proper position for the first step in the formation of the joint. Fig. 3 is a similar view and illustrates the first fold. Fig. 4 is a similar view and 35 illustrates the position of the parts in the finished joint. Fig. 5 is a perspective view of the finished joint duly soldered.

The letters C and C' designate two adjoining strips of tin roofing with edges upturned 40 in readiness for the formation of the joint. It will be noticed that in the initial stage the turned-up edge a of one strip C stands higher than the turned-up edge b of the other strip C'. In forming the joint the first fold is made by 45 turning the higher edge a over the lower edge b and then downward somewhat, as seen in Fig. 3. The second operation consists in bending both upturned edges a b at a proper point d a little below the cut down edge of the 50 first fold in a direction reverse from the first fold and leaving it projecting laterally and inclined downwardly, as shown in Fig. 4. This operation places the cut edge, which in the first fold was pointing downward, as in Fig. 3, in 55 an inclined upward position, and the second

bend at d is rounded instead of abrupt. When a folded joint on a roof has this inclined flange e projecting laterally from the vertical or up-standing part, it may be readily inspected and is accessible to the tools used for closing it. 60 The cut edge of the first fold is on top of the inclined flange e, where solder may be easily applied. The lateral position of the flange enables the metal of the seam parts to be heated by the soldering-tools, and the inclined 65 position of the flange causes the solder to flow down and sweat into the folded seam parts, all of which insures a tightly-soldered joint. The solder is designated by the letter f in the finished joint. (Shown in Fig. 5.) 70 This construction of joint admits the use of cleats of the same kind that are commonly employed with ordinary standing joints for anchoring or fastening tin roofs to the wooden structure. A standing expansible joint of 75 this construction will not have hurtful breaks or cracks in the metal at the cross-seams g, because the exposed bend d of this joint is gradually rounded and not abrupt.

As the finished joint has an inclined flange 80 projecting laterally from the standing part, there is an open space beneath the joint wherein water during rain-storms will freely flow and which will consequently be kept clean of dirt and will dry, and thereby avoid 85 the production of rust.

Another advantage of this form of finished joint for roof-seams is that the inclined flange projecting laterally serves to greatly stiffen and strengthen the standing joint. 90

Having thus described my invention, what I claim as new, and desire to secure by Letters Patent, is—

In a sheet-metal roof having a standing joint uniting two adjoining strips, the combination of a rounded bend in both upturned adjoining edges forming a down-inclined flange projecting laterally from the standing part; a fold of the lower sheet metal of the said flange upward and over the edge of the 100 upper sheet metal of said flange with the cut edge terminating on top; and solder on top of the flange and covering said cut edge and also sweated into the joint, as set forth.

In testimony whereof I affix my signature 105 in the presence of two witnesses.

HENRY O. REESE.
